(57) **CLAIM**

The ornamental design for a part of a baby carrier, as shown and described.

DESCRIPTION

FIG. 1 is a front perspective view of a part of a baby carrier showing our new design,

FIG. 2 is a right side view thereof,

FIG. 3 is a left side view thereof,

FIG. 4 is a front view thereof,

FIG. 5 is a rear view thereof,

FIG. 6 is a top view thereof; and,

FIG. 7 is a bottom view thereof.

The dotted lines located adjacent to the buckle are for illustrative purposes only and form no part of the claimed design. All other broken lines located within solid outlines represent stitching which is being claimed.

1 Claim, 7 Drawing Sheets
